CARTON

Raymond Chemlinski, Schenectady, N. Y.

Application February 8, 1946, Serial No. 646,284

2 Claims. (Cl. 229—16)

1

The object of my invention is to provide a carton particularly suitable to enclose an ink bottle for individual use. The carton is made in such a manner that it may be set up as a stand for said ink bottle, and that certain parts of said carton may be set up to form a rack for support of pens and pencils.

A further object is to make the carton simple in design, so that on the whole it does not materially depart from the structure of the conventional cartons.

I shall now describe my improvement with reference to the accompanying drawings, in which:

Fig. 1 is a perspective view of the carton in its closed position.

Fig. 2 is a perspective view of the carton in its partly set up position, in order that it may serve as an ink stand and a pen rack.

Fig. 3 is a perspective view of my carton as fully set up to serve as an ink stand and a pen rack.

Fig. 4 is a sectional view on line 4—4 of Fig. 3.

Fig. 5 is a sectional view on line 5—5 of Fig. 2.

Fig. 6 is a plan view of an end closure of the carton.

Similar numerals refer to similar parts throughout the several views.

The carton in its closed position is rectangular in shape, having the conventional form of cartons in which bottled ink for individual use is supplied. Fig. 1 shows the normal appearance of the carton as it would look with a bottle enclosed therein, although the bottle is not shown. As appearing in this position it includes four upright walls, namely, 10 which is the back wall, 11 and 12 which are side walls, and 13 which is the front wall. What appears as the bottom of the carton in Fig. 1 includes two flaps 14, extending from side walls 11 and 12, respectively, and an intermediately disposed closure 15 including a tongue 16. The top, as shown in Fig. 1, is made up of analogous parts, including flaps 17 and a closure 18 terminating with a tongue 19.

Now I wish to point out certain features which impart an inventive novelty to the structure of my said carton. It will be noted that one of the side walls 12 is cut along line 20, the line running from a point spaced from the top on the side of said wall 12, to a point at the lower level on the opposite side of the wall, wherefrom the continuation 21 of said line 20 runs parallel to the bottom end of the carton, severing the front wall 13 to a point spaced from side wall 11, as shown in Fig. 1. It will be further noted that flaps 14 include partly severed semicircular stays

2

22, which may be bent inwardly, leaving semi-circular openings 22a.

When it is desired to convert the carton into an ink stand, the bottle of ink that may be inside is first removed by swinging upwardly top closure 18 and flap 17, whereupon the carton is laid on a flat surface such as the top of a table, on what appears in Fig. 1 to be its back wall 10 so that the front wall 13 in said Fig. 1 becomes top wall, as shown in Fig. 3. Flaps 14 are bent outwardly, being disposed perpendicularly, stays 22 are pushed out towards each other, whereupon closure 15, which tends to assume a horizontal position, is swung upwardly from its connecting line with bottom 10 and past said stays 22. The stays, projecting outwardly from flaps 14, will prevent said closure 15 from returning back to its horizontal position. Tongue 16 will project upwardly. As a result, the flaps and the closure 15 with its tongue 16 will form a rack of the kind shown in Fig. 2, adapted to support pens and pencils. A pen 24 is shown in dotted lines for illustration.

As the next step in converting the carton into an ink stand, a part of side wall 12, namely, the part shown in Fig. 1 as being above line 20, is pushed inwardly towards the interior of the carton till it comes to rest on wall 10 in Fig. 1, which wall is the bottom member of the carton as it appears in Fig. 3. The bent in portion of wall 10, being affixed to wall 13, will cause a part 23 of said wall, appearing above line 21 as shown in Fig. 1, to assume a new position at right angle to said bottom as shown in Fig. 2. The remaining L-shaped part 29 of wall 13 will remain in its original position. End closure 18 shown best in plan view in Fig. 6, is folded along a creased line 25, causing the rest of said closure to form an inverted L-shaped formation, indicated by numeral 26 in Fig. 2, which is adapted to fit inwardly between top wall 13 and the side wall 11 and the bent in part 23 of said wall 13. The carton with said formation 26 fully inserted in its place is shown in Fig. 3. Lines 27 and 28 are the lines along which closure 18 has to be bent into said formation 26. When said formation 26 is in place between part 23 of wall 13 and side wall 11, said carton provides a space open from top for disposal therein of an ink bottle, the body of which will extend laterally under part 29 of top wall 13 as shown in Fig. 3. From the opposite side the bottle may be retained in place by flap 17, which is folded along line 30 to make a V-shaped wedge 31.

Having described my improvement, what I wish to claim is as follows:

1. A rectangular carton of the kind described, comprising a back wall, a front wall, two side walls, a closure at each end extending from said back wall, and a flap at each end of each side wall and extending in the plane thereof, one of said end closures being adapted to be swung away from the body portion of the carton to an inclined position, means on the adjoining flaps to lock said end closure in said inclined position, one side of the carton being cut diagonally from a point spaced from the top of the carton to a point spaced to the bottom of the carton, the cut continuing laterally across a part of the width of the front wall, the part of the side wall above the cut and the part of the front wall directly above the cut and defined by a line running from the end of the cut upwardly, being bent inwardly into the body of the carton, leaving an L-shaped part of the carton in its original position, the end closure adjoining said inwardly-bent part of the sidewall being adapted to be folded and partly inserted into the upstanding part of said body portion, while the end closure at the opposite end may be swung to a reclining position with respect to the body of the carton and locked in place by interlocking tabs on the adjoining flaps.

2. A carton cut, bent and formed from a single blank of material to include a back wall, a front wall, and two side walls to form a rectangular body, each end of the carton being provided with

a closure extending from the back wall and a flap extending from each side wall and extending in the plane thereof, one side wall being cut diagonally across its width from a point spaced from the top end of the carton to a point spaced from the bottom end of the carton, the cut continuing from said point laterally across a part of the front wall, the part of the side wall above the cut, and the part of the front wall above the cut therein and defined by a line running upwardly from the end of the cut, being bent inwardly until the part of said side wall is in parallel, abutting position with the back wall, leaving an L-shaped section of said front wall at its former level, the closure at the end adjoining the upstanding part of the side wall being bent away from the body of the carton to a slanting position towards said body and being held in place between the adjoining flaps to form a pen rack.
